DUSTPROOF SHOE BAG

Sophie Leader, New York, N. Y.

Application October 18, 1943, Serial No. 506,709

3 Claims. (Cl. 150—1)

This invention relates to a utility bag for various articles, such as brushes and particularly for shoes.

More particularly, it is an object of my invention to provide a bag with various pockets having a dustproof cover for such pockets.

A further object of my invention is to provide a cover for pockets for a shoe bag, said cover being attached on the bias so that there will be enough give and stretchability to the material to provide for ample room for the heel portion of the shoe.

A further object of my invention is to provide a dustproof cover set on the bias for pockets for a shoe bag to provide sufficient overhang over the top edge of the pocket so that ample room is provided for articles placed within the pockets.

A further object of my invention is to provide spacing between the snap fastener of the dustproof flap and the coacting fastener of the pocket to cover the pockets preventing dust from settling on the articles, such as shoes, after the articles are placed within the pockets.

For a fuller understanding of the nature and object of my invention, reference is had to the following detailed description in connection with the accompanying drawing, in which:

Fig. 1 is a front view of the container showing the dustproof flaps covering the empty pockets.

Fig. 2 is a sectional view taken along line 2—2 of Fig. 1.

Referring to the drawing, numeral 10 designates the back of the bag made preferably rectangular in shape, as shown in Fig. 1, the material being cut on the straight. The upper end of the material 10 is folded over to form the top strip 11. The cross pieces 12 and 13 are stitched along their lower ends and at their sides to the back 10. Cross pieces 12 and 13 are also stitched to the back longitudinally, thereof, thus dividing the cross pieces to constitute pockets 14 and 15 in the upper and lower cross pieces 12 and 13, respectively. Intermediate the points of which the cross pieces 12 and 13 are stitched to the back 10 the former are folded as shown at 16 whereby an enlarged pocket is produced.

Cross dustproof pieces 17 and 18 are stitched at their upper ends along stitch lines 19 and 20, respectively. Cross pieces 17 and 18 are cut on the bias in order to provide give and stretchability to the material and are also stitched

along their sides beneath binding tapes 21 and 22 along stitch lines 23 and 24.

At the top of each pocket there are male fasteners 25 while at the lower end of the cross pieces 17 and 18 there are female snap fasteners 26 to coact with male fasteners 25. It should be noticed that there is a small distance between the male and female fasteners 25 and 26.

When articles, such as shoes, are placed within the pockets 14 and 15, the heels of the shoes create a bulge at the top of the pockets and the bias cut pieces 17 and 18 stretch over the bulge created by the heels of the shoes so that the snap fasteners 25 and 26 can be snapped together to provide a covering for the pockets and the articles within the pockets. Both the stretchability of the bias cut pieces 17 and 18 and the distance provided between the male and female snap fasteners 25 and 26 give ample room for the bulge of the articles within the pockets 14 and 15.

Eyelets 27 are provided at the top 11, so that the bag may be conveniently suspended usually on the inside of the closet door.

Since the material of the pockets 14 and 15 and the back 10 are cut on the straight little or no sagging or give results so that the weight of the articles placed within the pockets of the bag are held in position by the support of the warp threads of the fabric. The cross pieces 17 and 18 are attached to the back cut on the bias in order to give stretchability and ample room for covering the pockets and the articles therein, so that no dust will fall upon the articles within the pockets.

It is obvious that various changes and modifications may be made in the details of construction without departing from the general spirit of the invention, as set forth in the appended claims:

I claim:

1. A bag of the character described, comprising a back of material on the straight, cross pieces stitched to said back at the bottom, sides and intermediate thereof, said cross pieces having portions folded inwardly so that the ends of the folded portions are a short distance from each other producing enlarged pockets, said back having its upper end folded over and stitched transversely thereof to form a top reinforcing strip for said bag, a plurality of eyelets spaced at predetermined distances along said top strip, cross dustproof pieces for said pockets on the bias covering the tops of said pockets to provide lateral stretchability, the bottom of said cross

dustproof pieces having means for fastening to said pockets, said cross pieces providing a dust-proof cover for said pockets.

2. A shoe bag comprising a back set on the straight, cross pieces forming pockets therewith set on the straight and stitched to said back, cross dustproof pieces set on the bias to provide lateral stretchability, and overlapping the tops of said pockets, fastening means at the top of said pockets and at the bottom of said cross dustproof pieces, said fastening means being spaced apart, whereby articles placed within said pockets will be covered by said cross dustproof pieces providing ample room for said articles when the fastening means are joined together.

3. An article bag of the character described comprising a substantially rectangular back set

on the straight, said back overlapping the top to form a reinforcing cross strip, cross pieces set on the straight and stitched to the back at the bottom, at the sides, and intermediate thereof with folded portions therebetween to form pockets, dust-proof cross pieces set on the bias to provide lateral stretchability and stitched at the tops, said cross pieces covering and overlapping the top of said pockets, fastening means at the tops of said pockets and at the bottom of said dustproof cross pieces providing a small distance between said fastening means, whereby said dust-proof cross pieces permit the insertion of articles within said pockets providing ample material to cover said articles to prevent dust from gathering upon such articles.
